(57) **CLAIM**

The ornamental design for a powered irrigator for sinus cavity rinse, as shown and described.

DESCRIPTION

FIG. 1 is a top, right, front isometric view of a powered irrigator for sinus cavity rinse.

FIG. 2 is a right elevation view of the powered irrigator for sinus cavity rinse of FIG. 1.

FIG. 3 is a left elevation view of the powered irrigator for sinus cavity rinse of FIG. 1.

FIG. 4 is a front elevation view of the powered irrigator for sinus cavity rinse of FIG. 1.

FIG. 5 is a rear elevation view of the powered irrigator for sinus cavity rinse of FIG. 1.

FIG. 6 is a top plan view of the powered irrigator for sinus cavity rinse of FIG. 1; and,

FIG. 7 is a bottom plan view of the powered irrigator for sinus cavity rinse of FIG. 1.

The broken lines shown in the drawings are for purposes of illustrating use and environment only and form no part of the claimed design.
